BLADE HOLDER FOR STROPPING MACHINES

Filed Aug. 25, 1919

Inventor:
Clarence E. Smith,
By L. M. Threlkeld
Atty.

Patented Apr. 17, 1923.

1,451,790.

UNITED STATES PATENT OFFICE.

CLARENCE E. SMITH, OF PEORIA, ILLINOIS.

BLADE HOLDER FOR STROPPING MACHINES.

Application filed August 25, 1919. Serial No. 319,799.

To all whom it may concern:

Be it known that I, CLARENCE E. SMITH, a citizen of the United States, residing at Peoria, in the county of Peoria and State 5 of Illinois, have invented certain new and useful Improvements in Blade Holders for Stropping Machines; and I do hereby declare that the following is a full, clear, and exact description of the invention, which 10 will enable others skilled in the art to which it appertains to make and use the same.

This invention relates to a device for use in stropping razors. It pertains more particularly to a structure for holding the 15 blade of a razor while being subjected to the stropping process.

The main object of the invention is the provision of a structure adapted for holding securely any type of safety razor blade, 20 whereby it may be properly stropped.

Another object is the provision of a structure part of which may be slidable relatively to a companion part, the two adapted to hold between them the blade to be sharpened, such structure having provision for receiving and holding a blade of one type and adapted also to receive a "filler," the latter adapted to receive and hold another type of blade.

30 Besides the above objects the invention consists of certain details of construction to be pointed out herein.

To the end that my invention may be more clearly understood, I have provided 35 the accompanying drawings wherein:

Figure 1 is a side elevation of my invention in one of its positions showing parts in section.

Figure 2 is a similar view showing one 40 of the members thereof in a different position from that shown in Figure 1.

Figure 3 is a transverse section of part 45 of the device on line 3—3, Figure 2, showing one type of razor blade held therein.

Figure 4 is a transverse section of the device on line 4—4, Figure 2, including the same type of razor blade.

Figure 5 is a transverse section of the device showing a "filler" member therein for holding a different type of blade from those 50 shown in Figures 3 and 4.

Figure 6 shows parts of the device in perspective.

Figure 7 shows in perspective another 55 part as companion to that of Figure 6 with the filler member therein.

Figure 8 shows in perspective another type of filler member from that shown in Figure 7.

Figure 9 is an end elevation of parts of 60 the device, and

Figure 10 is a longitudinal section of parts of the same.

The device herein is adapted for attachment to a stropping machine of that type, 65 for example shown in my pending application No. 308,416, filed July 3, 1919, I having shown herein but sufficient structure to make the present invention understood.

A indicates a support having the form of 70 a U, for example, its end portion being denoted by the letter B. Each of said end

portions is provided with a hole B' to receive certain members to be described presently, one of said holes being extended into communicating slots or recesses B². C

represents an inverted trough-shaped member, preferably of thin sheet metal, having longitudinal flange portions D at its edges, 75 as most clearly shown in Figure 6. E is a semicircular portion to which one end of the described member C is attached in any suitable manner, said disc member E being adapted to seat in the hole B' of one of the end members B, Figure 2. G is a similar

80 semicircular portion spaced from the member E, the two practically constituting a disc adapted to rock in the member A, one of the positions of rocking movements being shown in Figure 9 in broken lines. The two portions E and G are secured in any

85 suitable manner to a plate H, said plate H adapted to lie against the end B in which the said portions E and G are seated. The

90 end of the member C opposite that having the disc portions E and G has an extended ear J, adapted to pass through a disc K

95 which is also seated in the opposite end B of said member A, said ear also passing through a second disc L which lies outside of and against the said end, Figures 1 and 2, the disc L and the plate H serving to hold the structure thus described in position

100 with respect to the member A as against endwise movement.

In Figure 7, M denotes a portion which is companion to the portion C described, this also being of a trough-shape and provided with the substantially identical longitudinal flanges N. This member has at

105 its rear end, at each side, a hook O bent up therefrom to engage the two flanges D be-

fore described, serving to act as guides in the shifting movements of said member M as will appear presently. The outer end of the member is provided with a finger piece 5 P upon which is mounted a plate Q held by means of the screw R, for example, said plate at one edge overhanging the trough portion of the member, as most clearly shown in Figure 10. When assembled the 10 device appears as in Figures 3, 4 and 5, the trough members having between them the razor blade to be sharpened, or the filler member to be described, or both.

In Figure 1 the device is shown in position for operation, while in Figure 2 one of the portions of the member N has been withdrawn to receive the razor blade. It is to be observed that in said Figure 2 the upper surface of the member M and its trough are 20 exposed because withdrawn from beneath the member C and therefore the razor blade may be placed in position thereon and then pushed back to its normal or closed position shown in Figure 1, the blade being carried beneath the lower surface of the member C, both members C and M acting to virtually clamp such blade. In Figures 3 and 4 a certain type of blade is shown, the said blade being mounted in a head S, the 30 blade itself being indicated at T.

The head S may take up the entire space provided between the two members C and M, sufficient space being provided for that purpose, the blade protruding from between 35 the flanges D and N. Where a thin "wafer" blade is to be accommodated it is preferably carried by means of the filler member denoted at U in Figure 7. Still another form of this member is shown in Figure 8 and 40 designated by V. The first type of filler is that suitable for receiving a blade having perforations after the manner of the Gillette type, there being posts W in said plate U to enter said perforations whereby to 45 hold the blade firmly in position while being stropped. It is noted in this instance that the filler practically fills the trough of the member M, the edges of the blade projecting from the flanges D, N, as shown in 50 Figure 5, the posts W in that figure extending into the upper trough portion of the member C. The filler member V is provided with a depression X which takes the 55 razor blade whose ends at one edge are extended into portions Y to rest in a depression 1 of the same form. The plate H has a slot 2 therein to permit the edges of the blade in either form to pass through, the recesses B² in the adjacent end portion B 60 allowing of such passage. The slot 2 is enlarged below to permit entrance of the member M, permitting that member to have longitudinal movement therethrough as the blade is inserted or withdrawn from the stropping position, said slot being further 65

extended at its top to permit the head S of the blade shown in Figure 3 to readily pass in and out.

My device is universal in its application in that any type of razor blade may be 70 placed therein. If the owner of the device uses but one particular style of razor which employs a wafer blade, a filler member may be permanently held in place beneath the plate Q, whereas if other types of blades are 75 employed, such as that shown in Figures 3 and 4, for example, then the filler may be removed to accommodate them. Any filler, of course, may be used that will accommodate the particular form of blade that may 80 be used.

I am not aware of any device for stropping razor blades in which separate filler-members may be employed by which various 85 types of blades can be accommodated in the one stropping machine. I may make slight changes throughout the device such as may suggest themselves.

Having thus described my invention, I 90 claim:

1. In combination, a pair of channelled members lying one upon the other with their channels lying parallel to and facing one another, one of the members having extensions to hold the other in slidable relation, 95 said members adapted to receive between them a razor-blade and a carrier for said blade, a disc carried at each end of the member having the extensions, a U-shaped member having an opening in each extremity, 100 one opposite the other, the channel members lying between the said extensions, each hole adapted for receiving one of the discs, and means to retain the discs in the openings including a plate affixed to one of them, the same lying against one of the said extensions, said plate having a slot therein arranged parallel to the plane of the channelled members and lying opposite the place of abutting of the latter upon one another, said slot being adapted for permitting withdrawal therethrough of one of the channelled members, the carrier, and the blade lying therein.

2. In combination, a U-shaped member, 115 an inverted trough-like member lying between the extremities thereof journaled at one end in one of said extremities, a disc-like member fixed at the other end and journaled in the other extremity of the U-shaped member, that end of the member to which the disk-like member is affixed having an opening therein coextensive with the diameter of said disc-like member, the latter being of two parts spaced in the same plane with the trough of said trough-like member, and a second trough-like member slidably engaging the first said trough-like member and adapted to be withdrawn between the separated disc portions.

3. In combination, a U-shaped member, an inverted trough-like member lying between the extremities thereof journaled at one end in one of them, a disc-like member fixed 5 at the other end and journaled in the other extremity of said U-shaped member, a member to which the disc-like member is affixed having an opening therein coextensive with the diameter of said disc-like member and 10 extending at diametrically opposite points into two notches, said disc being separated into two parts in the same plane with the trough of the said trough-like member, the line of separation of the parts adapted to 15 register with the notches, and a second trough-like member slidably engaging the grooved side of the first trough-like member adapted to be withdrawn between said parts and through the said notches.
- 20 4. In combination, a U-shaped member, an inverted trough-like member lying between the extremities thereof journaled at one end in one of them, a disc-like member fixed relatively to the other end and journaled in the

other extremity of said U-shaped member, 25 a member to which the disc-like member is affixed having an opening therein coextensive with the diameter of said disc-like member and extended into a notch, said disc-like member being separated into two parts 30 in the same plane with the plane of the grooved side of the trough-like member, the line of separation of the parts adapted to register with the said notch, a second trough-like member slidably engaging the 35 said grooved side of the inverted trough-like member adapted to be withdrawn between the separated disc-like parts, and a blade holding device mounted between the two trough-like members and carried by the 40 second named one.

In testimony whereof I affix my signature in presence of two witnesses.

CLARENCE E. SMITH.
